DESIGN FOR A COMBINED VENDING AND WEIGHING MACHINE CASING

Newton E. May, South Bend, Ind., assignor to
National Syndicates Incorporated, South Bend,
Ind., a corporation of Indiana

Application December 13, 1933, Serial No. 50,059

Term of patent 7 years

To all whom it may concern:

Be it known that I, NEWTON E. MAY, a citizen
of the United States, residing at South Bend, in
the county of St. Joseph and State of Indiana,
have invented a new, original, and ornamental
Design for a Combined Vending and Weighing
Machine Casing, of which the following is a speci-
fication, reference being had to the accompanying
drawing, forming a part thereof.

Figure 1 is a front elevational view of a casing
embodying my new design.

Figure 2 is a side elevational view thereof.

Figure 3 is a top plan view thereof.

I claim:—

The ornamental design for a combined vending
and weighing machine casing as shown.
